HELICOPTER KITE TOY

Walter P. Tolomizenko, 240 Ellis Ave.,
Toronto 3, Ontario, Canada

Filed Apr. 23, 1970, Ser. No. 22,602

Term of patent 14 years

Int. Cl. D21—01

U.S. Cl. D34—15

FIG. 1 is a perspective view taken from a point slightly above and to one side of the forward portion of the helicopter kite toy;

FIG. 2 is a side elevational view of the helicopter kite toy of FIG. 1, but with the rotor disposed to lie in the plane of the elongated body;

FIG. 3 is an elevational view taken from the rear of the helicopter kite toy of FIG. 1, but with the rotor disposed at an angle to the position illustrated in FIG. 1;

FIG. 4 is a plan view of the helicopter kite toy of FIG. 1, but with the rotor disposed at still another angle to the position illustrated in FIG. 1.

I claim:

The ornamental design for a helicopter kite toy, as shown.
